(57) **CLAIM**

The ornamental design for a radiation shielding container lid, as shown and described.

DESCRIPTION

FIG. 1 is a perspective view of a radiation shielding container lid;

FIG. 2 is a top plan view of the lid of FIG. 1;

FIG. 3 is a cross section view thereof taken along line 3—3 in FIG. 2;

FIG. 4 is a cross section view thereof taken along line 4—4 in FIG. 2;

FIG. 5 is a front elevation view thereof, the rear elevation view being identical thereto;

FIG. 6 is a left side elevation view thereof, the right side elevation view being identical thereto; and,

FIG. 7 is a bottom plan view thereof.

The broken lines in the drawings are included for the purpose of illustrating portions of the radiation shielding container lid that form no part of the claimed design.
